UNITED STATES PATENT OFFICE.

JOHN N. BRATTON AND WALTER N. BRYANT, OF CHASE CITY, VIRGINIA.

SHOOK-SORTING MACHINE.

Application filed May 17, 1926. Serial No. 109,580.

This invention relates to new and useful improvements in sorting machines, and particularly to machines for sorting box shooks. One object of the invention is to provide a machine by means of which box shooks of varying widths are properly sorted, according to their widths, and deposited in containers.

Another object is to provide a novel and improved means for automatically ejecting like sizes of shooks from the machine.

Another object is to provide a machine wherein those shooks which have passed from one end of the machine to the other without having been ejected, are returned past a series of ejectors which resort such shooks.

A further object is to provide a novel means for maintaining the shooks in contact with the carrier, and for guiding such shooks to the ejectors.

Other objects and advantages will be apparent from the following description when taken in connection with the accompanying drawings.

In the drawings:

Figure 1 is a side elevation of a shook sorting machine made in accordance with the invention.

Figure 2 is an end view of the same.

Figure 3 is a vertical transverse sectional view on the line 3—3 of Figure 1.

Figure 4 is a vertical transverse sectional view on the line 4—4 of Figure 1.

Figure 5 is a horizontal fragmentary sectional view on the line 5—5 of Figure 1, looking downwardly.

Figure 6 is a plan view of part of the feeding mechanism.

Referring particularly to the accompanying drawings, 10 represent suitable supports to which are connected the longitudinal angle rails 11, 12, 13, and 14. The rails 11 and 13 having the horizontal wings directed inwardly toward the center of the machine, while the rails 12 and 14 have their horizontal wings directed outwardly, as clearly seen in the transverse sectional view Figure 3. Mounted on the ends of the

50 machine, and extended therefrom, are the brackets 15, in which are supported the sprocket wheels 16. Engaged around these sprocket wheels, and extending throughout the length of the machine, is the endless carrier chain 17, said chain having the shooks engaging lugs 18, at regularly spaced inter-

vals. It will be noted that the lower lap of the carrier chain moves in a plane just above the upper edge of the vertical wing of the lowermost angle rail 14, while the upper lap moves in a plane immediately above the upper edge of the rail 12, so that the lugs 18 project outwardly beyond said edge for engagement with the shooks which slide along on the horizontal wings of the rails 12 and 14, as will be explained more clearly hereinafter. As clearly seen in the sectional view, Figure 3, the chain, angle rails, and the parts to be later described, are duplicated at the other side of the machine, whereby shooks are simultaneously fed on both sides of the machine. On the intermediate portion of the shaft 16', of the sprocket wheels, at one end of the machine, there is mounted a belt wheel 19, which receives power from any suitable source by means of the belt 20.

Mounted on the horizontal wing of the rail 13 are the brackets 21, and secured to each bracket, and depending to a point directly outwardly of the lower lap of the chain, is an arm 22, a horizontal spring finger 23 being secured to the lower end of the arm for inward pressing engagement with the outer wider face of a box shook, to hold the shook against the chain. Also secured to the said bracket 21 is a spring arm 24 which extends downwardly for engagement with the upper edge of the shook to hold the same on the horizontal wing of the lower rail 14. It will be noted that the arms 22 are so spaced apart that a traveling shook will, while being engaged by one finger 23, engage beneath the next adjacent finger 23, so that there will be no danger of the shook accidentally falling from the rail 14.

It will be noted that the vertical wing of the rail 13 extends downwardly to within a short distance above the upper edge of the vertical wing of the lower rail 14, with the result that the space therebetween provides a slot extending through the length of the machine. Carried by the rails 13 and 14, intermediate the arms 22, are bearings 25, and mounted in these bearings are the vertical rock shafts 26. Carried by each of the shafts 26, and adjustable longitudinally as well as rotatably thereon, are the cam members 27 and 28, the latter of which play with in the slot between the rails 13 and 14, while the former move through longitudinal slots 29 formed in the vertical wing of the rail

13. The nose 27' of the cam 27 normally projects beyond the outer face of the chain, and in the path of the traveling shooks, for engagement by a shook of sufficient height, 5 which will cause the cam members to be swung outwardly and the shook to follow therewith. This movement of the cam member 27 causes the shaft 26 to rock with the result that the other cam member 28 10 will swing outwardly and engage the inner wider face of the shook, adjacent its lower edge, so that the shook is moved from its seat on the rail 14, and permitted to fall into a suitable bin or receptacle 30 directly 15 therebeneath. In this connection it will be noted that there is a bin or receptacle beneath each of the shafts 26, for receiving a certain width of shook which has been kicked from the rail 14 by a cam member 20 28. Each of the cam members 27 and 28 is adjustable by means of a screw 31. Encircling the lower end portion of each shaft 26 is a coil spring 32, one end being secured to the shaft and the other end being 25 secured to the rail 14, for yieldably holding the shaft in normal retracted position, so that the nose of the kicker cam 28 is disposed inwardly of the wing of the rail 13.

Secured to the outer face of the sprocket 30 wheel at the end of the machine which carries the driving pulley 19, is a beveled-edge disk 33, and disposed on the shaft 16', outwardly of this disk is a second disk 34, the same being spaced from the first disk, but 35 urged in the direction thereof by the coil spring 35. The peripheral edge of the disk 34 is also beveled, in the opposite direction to that of the first disk whereby to permit easy passage therebetween of a shook. It 40 will be noted that the end of the horizontal wing of the rail 12, adjacent the sprocket wheel above-mentioned, is turned downwardly, at 36, so that the shook, which has been gripped between the disks 33 and 34, 45 and carried around by the sprocket, will readily ride onto the said wing of the rail, to be carried along the machine in the direction of the hopper, which will be later described.

50 The arms 22, the shafts 26, and the cam members 27 and 28 carried thereby, are similarly mounted on the upper rails 11 and 12, for action upon the shooks which have passed the said members, while traveling 55 along the lower lap of the chain, and have been carried around by the disks 33 and 34.

Mounted on the end of the machine, remote from the disks 33 and 34, is a double hopper 37, in which the shooks are placed 60 so that they present their wider side faces toward the carrier chain. The forward end of the hopper is inclined rearwardly and outwardly from the side of the machine, and forming the bottom of the hopper are 65 the rollers 38, which extend at right angles

to the said inclined end of the hopper. On these rollers the said shooks rest, and slide toward the chain. Movable beneath the hopper adjacent the chain, and in line with the lower shook supporting rail 14, 70 is a feed chain 39, which has the lugs 40 for engaging the adjacent shook to move the same forwardly, out of the hopper, and into position to be engaged by a lug of the carrier chain 17, and sliding movement on the 75 rail 14. Extending longitudinally of the upper and lower portions of the machine frame are the rails or tracks 41, on which the laps of the carrier chain 17 are arranged to slide, certain of the links of said chain being provided with depending parallel flanges 42 for straddling said rails or tracks, to properly guide the chain. 80

It will be understood that the hopper is so constructed that a shook is automatically fed 85 to each side of the machine at the same time, whereby such shooks are sorted in pairs.

The spacing of the drag lugs of the hopper feed chain are such that each lug places a shook on the lower rail 14, and passes out 90 of engagement therewith just prior to the engagement of the shook by a lug of the carrier chain 17. The first of the shook gripping arms 22 is so spaced from the hopper that it engages and holds the shook before 95 being released by the carrier chain, thus providing for the proper retention of the shook in engagement with the carrier chain. The shook is carried along the rail by the chain 17 until a cam member 27 is reached 100 which is sufficiently low to be engaged by the shook, whereupon said shook presses the cam to such an extent that the cam swings outwardly away from the side of the machine, together with the advanced end of the 105 shook. This swinging movement of the cam rocks the shaft 26, with the result that the other cam member 28 is swung outwardly to push against the lower portion of the advanced end of the shook. The incline of the 110 nose of the cam member 27 is such that the advanced end of the shook will properly slide outwardly therefrom, when said cam is brought to a stop by engagement with the adjacent end wall of the slot 29. The spring 115 32 causes the return of the cam members to normal position after the shook has been ejected from the rail 14, and permitted to fall into its proper receptacle or bin. The return swinging movement of the cam members is limited by the engagement of the rear 120 side of the nose 27', of the cam 27, with the adjacent end wall of the slot 39. This permits said nose to project through the slot 39 to a sufficient distance to be properly engaged by the advanced end of a shook, while the nose of the cam member 28 is disposed out of the path of the said end of the shook, so that it can properly engage with the inner 125 wider face of the shook, after the cam mem-

130

- ber has been rocked to bring this cam member through the space or slot between the rails 13 and 14. If the shook is too narrow to have engaged any of the cam members 27, throughout the entire length of the machine, and has successfully passed the last, or lowest of them, the shook is extended into gripping engagement with the disks 33 and 34, by the carrier chain, and carried around the 10 sprocket wheel to be delivered onto the upper lap of the chain, being engaged by a drag lug thereof, and moved along the upper rail 12, in the direction of the hopper end of the machine. The shook passes retaining 15 arms 22, and cam members 27 and 28, on the upper portion of the machine, and if too small to engage and move any of the upper cams, such shook is discharged from the machine as non-useable, or too narrow for use.
- 20 The purpose of the sorting done by this machine is to segregate the like widths of shooks, so that the assembler of a box may quickly select, from the proper bins, the two mating sizes of shooks which will total a 25 width equal to the depth of the box to be made. These mating sizes, are then passed through a resawing machine which will trim the edge of one of the shooks so that the total width of the two shooks will be the 30 proper one for the box.
- While I have shown two supports 10, and three of the shook holding and sorting ejecting devices, it will be understood that the number may be increased to the extent desired, to accomplish the desired result within the limits of the space wherein the machine is located. The number of the above elements shown in the drawings is for purpose of illustration only.
- 40 The rails 12 and 14 are supported on the vertical slidable toothed racks 43, said racks being mounted on the uprights or supports 10. Properly mounted on the uprights or supports 10, and extending longitudinally of the machine, is a shaft 44 having toothed wheels 45 engaging the said racks, and having a hand wheel 46 on one end, whereby to elevate or lower the rails 12 and 14, in accordance with the widths of the shooks to be sorted. These racks 43 are formed with longitudinal slots 43', and the teeth formed on one wall of the slot, the shaft 44 extending through said slot.
- 50 Slidably adjustable on the rear face of the vertical wing of each of the rails 11 and 13, adjacent an end of each of the slots 29, thereof, is a plate 47 which is arranged to be engaged by the cam member 27, whereby to limit the outward swing under the influence of the shook.
- 55 What is claimed is:
1. A sorting machine including a carrier, a support for articles moved by the carrier, means for holding vertically adjustable articles engaged with the carrier, article actu- 60 ated means, and kickers associated with the article actuated means for actuation upon an article upon actuation of the latter by an article.
  2. A sorting machine including a carrier, an article actuated rocker, and a kicker carried by and actuated by the rocker.
  3. A sorting machine including a carrier, a rocker, article actuated means on the rocker, and a kicker on the rocker.
  4. A sorting machine including a carrier, a rock shaft, article actuated means on the shaft, and a kicker on the shaft.
  5. A sorting machine including a carrier, a rock shaft, article operated means on the shaft for rocking the latter, a kicker on the shaft, and means for yieldably maintaining the rocker in normal position.
  6. A sorting machine including a carrier, a rock shaft, means on the shaft having a nose normally in the path of an article on the carrier for rocking the shaft, and a kicker carried by and movable with the shaft.
  7. A sorting machine including a carrier, rock shafts, an article actuated means on each shaft, each of said means being in a different plane from that of the other means in regular progression, a kicker on each shaft, and means for yieldably maintaining the shafts in normal position.
  8. A sorting machine including a carrier, means for holding articles in engagement with the carrier, means for ejecting from the carrier articles of predetermined sizes prior to engagement with succeeding holding means.
  9. A sorting machine including a carrier, a support for articles moved by the carrier, means for holding articles engaged with the carrier, means for holding articles engaged with the support, and means for ejecting from the carrier articles of predetermined sizes prior to engagement thereof with a succeeding first-named holding means.
  10. A sorting machine including an endless carrier having its laps superimposed, supports for articles adjacent each lap of the carrier, ejecting means adjacent each lap of the carrier, and means for transferring articles from the lower to the upper lap of the carrier which have passed the ejecting means adjacent the lower lap.
  11. A sorting machine including an endless carrier having its laps superimposed, ejecting means adjacent the laps, article supports adjacent the laps, and means at one end of the machine for gripping articles from the lower lap which have passed the ejecting means of the lower lap and transferring the same to the upper lap.
  12. A sorting machine including an endless carrier having its laps superimposed, means adjacent the laps actuated by articles

of predetermined heights, kickers operated by said means for ejecting articles which engage said first means, article supports adjacent the carrier laps, and resilient gripping means for transferring articles from the lower support to the upper support.

13. A sorting machine including a carrier, a rock shaft, article operated means on the shaft for rocking the latter, a kicker on the shaft, and means for restoring the kicker to normal position after each operation thereof.

14. In a sorting machine, the combination

with a carrier, of a wall adjacent the carrier, a rock shaft adjacent the wall, an arm 15 on the shaft projecting beyond the wall in position to be engaged by an article on the carrier, and a second arm on the shaft adapted to be projected beyond the wall to eject the article from the carrier upon engagement of the first arm by the article.

In testimony whereof, we affix our signatures.

JOHN N. BRATTON.
WALTER N. BRYANT.
